VENETIAN BLIND

Harry Nelson, New York, N. Y., assignor to
 Lorentzen Hardware Mfg. Corp., New York,
 N. Y., a corporation of New York

Application July 2, 1946, Serial No. 681,042

13 Claims. (Cl. 160—173)

1

This invention relates to Venetian blinds, including a special construction of slats for such blinds.

In the conventional Venetian blind the slats are each provided with spaced apertures through which lift-cords are passed. The slats are conventionally supported in superimposed spaced relation by ladder tapes. By shifting these tapes, customarily accomplished by canting a tilt bar at the top of the blind, the individual slats may be simultaneously tilted in either direction in order to vary the amount of light passing through the blind. In addition, the blind may be raised by the lift-cords, stacking the individual slats upon the bottom rail as it is raised by the lift-cords.

The apertures provided in the individual slats for the lift-cords are customarily formed as transverse slots of sufficient length to permit the slats to tilt as required without flexing the lift-cords. The width of the slots is so chosen as to be slightly greater than the diameter of the lift-cords passing therethrough, whereby the cords act to maintain the slats in alignment longitudinally.

In accordance with the present invention, it is contemplated to have one or more of the apertures in each slat of such size and shape as to definitely position the slat longitudinally relative to the lift-cord passing therethrough. The remaining apertures of each slat may be of any desired shape, but sufficiently large so as not to engage the lift-cords passing therethrough, at least unless the slat is in extreme tilted position. Various forms of apertures will be disclosed, and if desired one or more or all of the lift-cord apertures of each slat may be of any of the forms shown in the accompanying drawings. However, I prefer that all of the holes except one in each slat be sufficiently large to normally remain clear of the lift-cord passing therethrough.

An object of the present invention is to substantially eliminate the fraying of Venetian blind lift-cords by the edges of the slats surrounding the lift-cord aperture, thus making for longer life of the lift-cords.

Another object of the invention is to reduce the friction between the lift-cords and the slats when raising or lowering the blind, thus making for easier operation and preventing the binding of slats on the lift-cords upon lowering which sometimes raises some of the slats off the transverse portion of the ladder tapes, thus positioning the slats irregularly.

A further object of the invention is to provide a construction that will allow for slight inac-

2

curacy in the spacing of the apertures of individual slats without rendering the blind defective and difficult in operation.

A still further object of the invention is to generally improve the construction of Venetian blind slats without substantial increase in cost.

Further objects will be apparent from a study of the detailed description which follows, made in conjunction with the accompanying drawings.

10 My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best forms in which I have contemplated applying my invention are illustrated in the accompanying drawings forming part of this specification, in which:

Fig. 1 is a fragmentary perspective view of the lower portion of a Venetian blind incorporating one form of my invention.

25 Fig. 2 is a fragmentary vertical section taken on the line 2—2 of Fig. 1.

Fig. 3 is a view of a fragment of a Venetian blind slat, showing in plan view the aperture shown in Fig. 2.

30 Fig. 4 is a view similar to Fig. 2 with the slat in tilted position.

Fig. 5 is a fragmentary vertical section taken on the line 5—5 of Fig. 1.

35 Fig. 6 is a cross section of a Venetian blind slat showing a modified treatment of the slat edge surrounding the aperture.

Fig. 7 is a view similar to Fig. 6 of a still further modification.

40 Fig. 8 is a perspective view of a fragment of a slat having an applied grommet secured by four clinched fingers. For the purposes of illustration two of the fingers are shown clinched and two unclinched.

Fig. 9 is a plan view of a fragment of a Venetian blind slat showing a further modification of the lift-cord aperture.

45 Fig. 10 is a detail section taken on the line 10—10 of Fig. 9.

Referring to Fig. 1 of the drawings, the Venetian blind embodies various conventional features, including conventional ladder tapes 11 which may be secured to a usual tilt bar (not shown) adjacent to the top of the blind. The lower ends of the ladder tapes are secured to a customary bottom rail 12 of the blind. In the

form shown, four lift-cords 14 are shown, but the number of lift-cords may be increased or decreased within the scope of my invention. Where the blind is of fairly narrow width, only two lift-cords are ordinarily used.

A plurality of slats 15 are positioned within the ladder tapes 11 in the conventional way, each having an aperture 16 and one or more apertures 17, a lift-cord 14 passing through each aperture. The slats 15 may be formed of any relatively thin sheet material. Sheet steel and aluminum are suitable materials, but plastic and other non-metallic materials may be used. The slats are preferably resilient and are preferably slightly arched transversely as shown so as to give greater longitudinal rigidity.

Inasmuch as normally all slats in any one blind will be similarly apertured, one slat will be described, it being understood that the remainder of the slats in the blind are preferably similar. The aperture 16 of the slat 15 preferably is a transverse slot formed in the slat interiorly of the edge thereof, as best shown in Fig. 3. The aperture 16 is preferably only slightly wider than the diameter of the lift cord 14. This permits the free passage of the cord through the aperture, while the cord serves to longitudinally position the slat 15 relative to the cord in order to maintain all of the slats in longitudinal alignment in the blind. Inasmuch as these slats are spaced and supported by the ladder tapes 11, the tapes maintain the slats in lateral alignment without the assistance of the lift-cords. Accordingly, the aperture 16 may be made sufficiently long to permit the tilting of the slats 15 to a nearly vertical position relative to the lift-cord 14, as shown in Fig. 4 as is customary, without affecting the lateral alignment of the slats.

In order to prevent the fraying of the lift-cord 14 by the edge of the slat 15 surrounding the aperture 16, the edge may be lined with a liner or grommet 18. The grommet 18 may be formed of any material supplying a smooth enlarged bearing for engagement of the slat 15 with the lift-cord 14, and it is preferably formed of a thin ductile metal, such as brass or aluminum. It may be applied to the aperture 16 by use of a conventional eyeletting machine.

Other apertures 17 of the slat 15 may be formed by stamping out portions of round or other desired outline but of a size to supply a relatively large clearance between the edge of each aperture 17 and its lift-cord 14. In order to provide for tilting of the slat 15, as well as providing an easily formed aperture, aperture 17 may be circular in outline of a diameter approximately equal to the greatest dimension of the aperture 16.

As best shown in Fig. 1, the slats 15 are maintained in longitudinal alignment by cooperation of one lift-cord 14 with the apertures 16 of the slats collectively, apertures 17 not aiding in maintaining alignment and being free from contact with lift-cords 14, except, perhaps, when the slats 15 are in fully tilted position. Accordingly, the edges of the slats 15 about aperture 17 do not fray their lift-cords 14 and there is no necessity for providing a lining or grommet 18 at this point. The grommet 18 obviates fraying of the lift-cord 14 passing therethrough, and the extra clearance between the slat 15 and the lift-cords 14 at apertures 17 permits a much greater tolerance in spacing of the apertures without adversely affecting the action of the blind or the life of the lift-cords.

Instead of inserting a grommet 18 in the aperture 16 of slat 15, the edge surrounding the aperture may be thickened and provided with a suitable smooth bearing surface by forming the sheet material so as to provide a smoothly rolled homogeneous edge R as shown in Fig. 6 or a homogeneous welded or coined edge C as shown in Fig. 7. These modifications are particularly suitable for a slat made of aluminum, plastic, or other easily worked material. While the Fig. 7 modification is difficult to apply to a steel slat, the Fig. 6 modification can be applied to a steel slat without undue difficulty. Both modifications provide a smooth bearing of the slat 15 on the lift-cord.

Referring to Fig. 8, a grommet 19 consisting of a relatively flat plate 20 having smooth upstanding or rolled edges defining a central elongated aperture 21, may be secured in the aperture 16 of the slat 15 by tongues 22 struck up from the corners of the plate 20. These tongues are inserted through the aperture 16 and clinched on the opposite face of slat 15 so as to secure the grommet 19 in position. For the purpose of illustration, two of the tongues 22 are depicted before clinching, and two after clinching. The plate 20 may be slightly arched to conform to the shape of the slat 15. This modification had the advantage of not requiring eyeletting or other machines for insertion of the grommet.

In lieu of some or all of the apertures 16 and 17 in slat 15 as above described, one or more apertures 23 (see Fig. 9) may be formed in each slat 15. The aperture 23 consists of a transverse slot wider relative to the lift-cord 14 than the aperture 16, and having centrally converging opposite end portions 24 and 25. A smooth and thicker bearing portion may be formed at these portions of aperture 23 by bending back tabs 26 struck from the slat 15, as shown in Fig. 9. It will be apparent that when the slats 15 are correctly aligned relative to the lift-cords 14, the edges of aperture 23 will not engage lift-cords 14 except when the slats are in fully tilted position. Upon tilting of the slats 15, the centrally converging end portions 24 and 25 of the aperture 23 will engage the lift-cord and serve to correct any misalignment of the slats 15 relative to the lift-cords 14, thus maintaining the slats in alignment. An aperture of the size and shape of aperture 23 is also advantageous when made as a plain stamped hole with tabs 26 eliminated.

The invention hereinabove described is particularly advantageous with steel or other relatively thin Venetian blind slats wherein the problem of preventing fraying of the lift-cords is particularly acute. However, this invention is also applicable to blind slats made of any other materials.

The slot, such as slot 16, should have a width somewhat greater than the diameter of the lift-cord, and it should have a length sufficient to permit the slat to tilt at least 45° without flexing the lift-cord. I have found that the length of the slot should be at least three times the diameter of the lift-cord, and I prefer that it be approximately five times the diameter of the lift-cord. I prefer that the width of the slot be approximately twice the diameter of the lift-cord. The apertures such as 17 should be of such size and shape that the edges thereof are free of the lift-cord when the slat is tilted 45°, and preferably, the edges should be free of the lift-cord at all times except, perhaps, when the slat is fully tilted. I prefer that all diameters of holes

such as 17 be at least three times the diameter of the lift-cord. Where an aperture such as 17 is a round hole, I prefer that its diameter be approximately five times the diameter of the lift-cord.

What I claim is:

1. In a Venetian blind having a plurality of thin sheet metal slats suspended one above another, the slats collectively having series of aligned apertures through which lift-cords extend, the improvement which comprises: the apertures of one series being elongated slots disposed transversely of the slats, and the apertures of the other series being round holes of a diameter approximately equal to the length of said slots, edge portions of the slots being smooth cord-engaging means of greater thickness than the metal of the slats.

2. In a Venetian blind having a plurality of slats suspended one above another, the slats collectively having series of aligned apertures through which lift-cords extend, the improvement which comprises: the apertures of one series being elongated slots disposed transversely of the slats, and the apertures of the other series being round holes of a diameter approximately equal to the length of said slots.

3. In a Venetian blind having a plurality of slats suspended one above another, the slats collectively having series of aligned apertures through which lift-cords extend, the improvement which comprises: the apertures of one series being elongated slots disposed transversely of the slats, the width of the slots being somewhat greater than the lift-cord diameter and the length of the slots being over three times the lift-cord diameter, and the apertures of the other series being holes all diameters of which are over three times the lift-cord diameter.

4. In a Venetian blind having a plurality of thin sheet metal slats suspended one above another, the slats collectively having series of aligned apertures through which lift-cords extend, the improvement which comprises: the apertures of one series being elongated slots disposed transversely of the slats, the width of the slots being somewhat greater than the lift-cord diameter and the length of the slots being over three times the lift-cord diameter, the apertures of the other series being holes all diameters of which are over three times the lift-cord diameter, and edge portions of the slots being smooth cord-engaging means of greater thickness than the metal of the slats.

5. In a Venetian blind having a plurality of thin sheet metal slats suspended one above another, the slats collectively having series of aligned apertures through which lift-cords extend, the improvement which comprises: the apertures of one series being elongated slots disposed transversely of the slats, the width of the slots being approximately twice the lift-cord diameter and the length of the slots being approximately five times the lift-cord diameter, the apertures of the other series being holes all diameters of which are approximately five times the lift-cord diameter, and edge portions of the slots being smooth cord-engaging means of greater thickness than the metal of the slats.

6. In a Venetian blind having a plurality of slats suspended one above another, the slats collectively having series of aligned apertures through which lift-cords extend, the improve-

ment which comprises: the apertures of one series being elongated slots disposed transversely of the slats, the width of the slots being approximately twice the lift-cord diameter and the length of the slots being approximately five times the lift-cord diameter, and the apertures of the other series being holes all diameters of which are approximately five times the lift-cord diameter.

7. In a Venetian blind having a plurality of slats suspended one above another, the slats collectively having series of aligned apertures through which lift-cords extend, the improvement which comprises: the apertures of one series being elongated slots disposed transversely of the slats, the end portions of the slots including converging straight-line edge sections, and the apertures of the other series being holes all diameters of which are over three times the lift-cord diameter.

8. In a Venetian blind having a plurality of thin sheet metal slats suspended one above another, the slats collectively having series of aligned apertures through which lift-cords extend, the improvement which comprises: the apertures of one series being elongated slots disposed transversely of the slats, the end portions of the slots including converging straight-line edge sections, the apertures of the other series being holes all diameters of which are over three times the lift-cord diameter, and the converging straight-line edge sections of the slots being smooth cord-engaging means of greater thickness than the metal of the slats.

9. In a Venetian blind, a head bar, a bottom bar, a tilt bar tiltably mounted on said head bar, ladder tapes depending from said tilt bar and secured to said bottom bar, a plurality of slats formed of thin sheet material having spaced apertures and supported on said ladder tapes, and lift-cords passing through said apertures to lift said bottom bar, a corresponding aperture of each of said slats consisting of a transverse slot, the sides of which are close to the lift-cord and maintain the slats longitudinally positioned, and the other apertures of each slat being sufficiently large to maintain the edges of such aperture out of contact with said lift-cords except when the slats are in fully tilted position.

10. A slat for a Venetian blind, said slat comprising: a strip of sheet material having spaced apertures arranged along its length, one of said apertures being a transverse slot adapted to cooperate with a lift-cord passed therethrough for longitudinally positioning said slat, and the other apertures being sufficiently large to maintain the edges of said apertures out of contact with said lift-cord except when the slat is tilted more than 45° with respect to a lift-cord passed therethrough.

11. A slat for a Venetian blind, said slat comprising: a strip of sheet material having spaced apertures arranged along its length, one of said apertures being a transverse slot adapted to cooperate with a lift-cord passed therethrough for longitudinally positioning said slat, and the other apertures being round and of a diameter approximately equal to the length of said slot.

12. In a Venetian blind having a plurality of slats suspended one above another, the slats collectively having series of aligned apertures through which lift cords extend, the improvement which comprises: each of the slats of said plurality consisting of a slat as claimed in claim 10.

13. In a Venetian blind having a plurality of slats suspended one above another, the slats collectively having series of aligned apertures through which lift cords extend, the improvement which comprises: each of the slats of said plurality consisting of a slat as claimed in claim 11.
